ATTORNEY

UNITED STATES PATENT OFFICE

146,754

DESIGN FOR A PIN OR SIMILAR ARTICLE

Murray Slater, Brooklyn, N. Y.

Application June 14, 1946, Serial No. 130,717

Term of patent 3½ years

(Cl. D45—19)

To all whom it may concern:

Be it known that I, Murray Slater, a citizen of the United States, residing at Brooklyn, in the county of Kings and State of New York, have invented a new, original, and ornamental Design for a Pin or Similar Article, of which the following is a specification, reference being had to the accompanying drawing, forming part thereof.

Fig. 1 is a top view; and

Fig. 2 is a plan view of a pin showing my new design.

I claim:

The ornamental design for a pin or similar article, as shown.

MURRAY SLATER.
